INVENTOR,
Joseph Warren Piper,
BY
Albert M. Moore,
ATTORNEY.

UNITED STATES PATENT OFFICE.

JOSEPH WARREN PIPER, OF LOWELL, MASSACHUSETTS.

BOILER FOR STEAM AND HOT-WATER HEATING.

1,398,794.

Specification of Letters Patent. Patented Nov. 29, 1921.

Application filed December 31, 1920. Serial No. 434,203.

To all whom it may concern:

Be it known that I, JOSEPH WARREN PIPER, a citizen of the United States, residing at Lowell, in the county of Middlesex and Commonwealth of Massachusetts, have invented a certain new and useful Improvement in Boilers for Steam and Hot-Water Heating, of which the following is a specification.

10 This invention relates to boilers for steam and hot water heating.

The object of said invention is to increase the heating surface of a boiler by the use of a water containing division, consisting of 15 spaced water tubes extending across the fire-chamber and from the top of said chamber, their lower ends being connected to a horizontal tube having closed ends, said horizontal tube being in proximity to the fuel 20 supporting surface but far enough above to allow the lower part of the fuel to extend under said division; having a water connection only at the top thereof with the body of the boiler and not being connected 25 with the return flow.

The division is held from displacement by its connection with the top of the fire-chamber and by any convenient means of securing its lower part from lateral displacement within said fire-chamber; preferably by recessing the walls of said chamber but without communication therewith.

This division separates the fire-chamber into two preferably equal parts, either or 35 both of which may be used at a time according to the requirements of the season.

The water leg or body of the boiler is correspondingly partitioned in such a manner as to leave one of the returns in communication with one of the compartments of said 40 water-leg and the other return in communication with the other compartment.

The boiler is more conveniently provided with two door openings on opposite sides of 45 the division but a single door opening as usual may be used if wide enough to give ready access to both compartments of the fire-chamber.

By this form of division a considerable 50 portion of the water is retained in circulation through said division and thereby continually subjected to the greatest heat of

the fire and being segregated from the general system is always in even temperature with the burning fuel, thus causing no detriment to combustion to even the slowest fire. 55

In the accompanying drawing Figure 1, is a horizontal section on the line 1 1 in Fig. 2, of the fire-chamber portion or body of a boiler provided with my improvement; Figs. 60 2 and 3 vertical central sections on the lines 2 2 and 3 3 respectively, in Fig. 1.

In the letters of reference B indicates the base of the boiler; G, the grate, D, the body or water-leg of the boiler; d, the fire-chamber; d¹, the door-openings; d², the water-space between the outer and inner shells of the boiler; d³, the flues; d⁴, in all figures, the partitions dividing the water-leg. F indicates the vertical tubes dividing the fire-chamber, F¹ is a horizontal water-tube having closed ends into which tube the vertical tubes are connected to form the divisional system and to secure a circulation separate and independent from the circuit through 75 the return H, by which the water returns to the boiler from the place heated. 70

C C are recesses or cavities in the wall of the fire-chamber to receive the ends of the water-tube F¹ and thereby to secure the division from lateral displacement. 80

In operation, the water of the return-flow, after entering as usual, through the outer wall of the boiler at the bottom of the fire-chamber, ascends the water-leg to the water-space over the fire, where said water is exposed to the direct action of the fire and receives additional heat from the extremely hot water of the vertical tubes of the divisional system. 85

I claim as my invention;

A house heating boiler having a fire chamber provided with recesses at the bottom thereof and with a transverse water containing division adapted to segregate the 95 water therein from the circuit of the house, and comprising a series of spaced water-tubes running from the top of said chamber downward and connected at their lower ends to a horizontal water-tube having 100 closed ends, said closed ends being secured in said recesses to prevent lateral displacement.

JOSEPH WARREN PIPER.
